UNITED STATES PATENT OFFICE.

JOHN C. LAURITZEN, OF AKRON, OHIO.

VULCANIZER.

1,256,704.

Specification of Letters Patent. Patented Feb. 19, 1918.

Application filed December 12, 1917. Serial No. 206,833.

To all whom it may concern:

Be it known that I, JOHN C. LAURITZEN, a citizen of the United States, and resident of Akron, Ohio, have invented certain new and useful Improvements in Vulcanizers, of which the following is a specification.

My present invention relates to improvements in vulcanizing presses of the type used more especially for vulcanizing auto-
10 mobile tires and aims to provide a simple, efficient and economical construction which will enable the use of a ram with a very short throw or stroke.

In previous press constructions of which I am aware it has been necessary to either provide material space beneath the vulcanizer for the location of the ram, or to excavate beneath the ground floor to provide such space, rendering the ram and pipe connections difficult to install, especially where rock is encountered, and difficult of access.

My invention includes the novel features of construction and arrangement and combination of parts hereinafter described and particularly defined by the appended claims.

An embodiment of my invention is illustrated in the accompanying drawings, in which,

Figure 1 is a sectional elevation of my improved vulcanizer.

Fig. 2 is a section on line 2—2 of Fig. 1.

Fig. 3 is a plan view of the mold carriage, and,

Fig. 4 is a sectional view of the same.

Referring by reference characters to this drawing the numeral 1 designates the vulcanizer chamber, or press tank, which may be of the ordinary or any desired construction, except as hereinafter specified, and provided with bottom closure 1^a, and top closure 1^b, detachably secured in position by any suitable means, as for instance the bayonet joint connections indicated at 1^c. The bottom closure 1^a is supported upon a base 2, which includes the ram cylinder 3, which, as shown is very short, and contains the ram piston 4, which has its upper end projecting through the packing 5. A ram cap 6 is supported upon the upper end of the ram piston, preferably by means of the depending central portion 6^a.

Supposing the ram cap to occupy the position shown in full lines in Fig. 1, and the space between it and the pressure flanges 1^d of the top closure or cover to be filled with superposed molds, it is only necessary to

impart a very slight vertical movement to the ram piston to apply the requisite pressure to the molds, and therefore the height of the ram can be reduced to a minimum. 60

It is necessary, however, that the ram cap shall be capable of being raised to the top of the press tank in loading and unloading, as the molds, with the inclosed tires on their metal cores, are extremely heavy, the practice in loading being to bring the ram cap to the level of the mouth of the press tank, to place one mold in position and thereafter lower the ram cap the height of one mold, 65 and repeat the operation for each successive 70 mold. The reverse operation takes place in unloading.

To accomplish this elevation of the ram cap without the use of the ram I provide what I term a mold carrier, which is indicated at 7, and which consists of a plate-like member having an open center 7^a and strengthening ribs, which member engages or projects beneath the edges of the ram cap, so that when the carrier is moved vertically 80 the ram cap will be elevated away from the ram piston.

A simple and effective means which I have found desirable for elevating the carrier comprises a plurality of vertical screw rods 85 having their upper ends journaled in suitable bearings 8^a carried at the top of the press tank, and projecting at their lower ends through suitable stuffing boxes 8^b in the tank bottom, their lower ends being stepped 90 in the bearings 8^c, these rods engaging split threaded bushings 7^b secured in openings in the carrier. These projecting portions carry worm gears 9, which mesh with worms 10 on shafts 11, journaled in suitable bearings 95 11^a, which shafts may be driven by sprocket chains 12 from a counter shaft 13, carrying a gear 14, meshing with a gear 15 on the shaft of an electric motor 16.

For convenience of illustration I have 100 omitted the pipe connections to the ram, as these form no part of the present invention.

What I claim is:

1. In combination, a press tank, a ram cap 105 therein, a ram having a movable element upon which said ram cap is removably mounted, and means for elevating and lowering said ram cap, independently of said movable element.

2. In combination, a press tank, a ram cap 110 therein, a ram having a movable element

upon which said ram cap is removably mounted, a carrier having a part projecting beneath the ram cap, and means for moving said carrier vertically.

5 3. In combination, a press tank, a ram cap therein, a ram having a movable element upon which said ram cap is removably

mounted, a carrier having a part projecting beneath the ram cap, a plurality of vertical screw rods within the press tank engaging 1. said carrier, and means for simultaneously rotating said screw rods.

In testimony whereof, I affix my signature.
JOHN C. LAURITZEN.
